UNITED STATES PATENT OFFICE.

PIERRE ZUCCO, OF NEW YORK, N. Y.

GIRDER OR BEAM.

No. 861,930.

Specification of Letters Patent.

Patented July 30, 1907.

Application filed December 6, 1906. Serial No. 346,614.

To all whom it may concern:

Be it known that I, PIERRE Zucco, a resident of the city of New York, county of New York, and State of New York, have invented certain new and useful Improvements in Girders or Beams, of which the following is a specification.

This invention relates to the construction of concrete or cement girders or beams, and more particularly to the manner of armoring same.

10 The object of this invention is to provide an armor for concrete or cement construction of the class above described, and to form the same in such a manner that it may be easily and quickly prepared for different structures.

15 A further object of the invention is to provide a steel bar having a bar integral therewith and an integral web, each adapted to be sheared and bent at angles therefrom so as to form a more durable reinforcement.

To this end I make use of a bar, the particular construction of which and the manner of shearing its various parts, will be more fully described and specifically pointed out in the appended claims.

In the drawings forming a part of this specification: Figure 1, is a side elevation of a beam showing my improved bar as applied, the beam being in section; Fig. 2, is a perspective view of a bar constructed in accordance with my invention; Fig. 3, is a cross sectional view of the bar; and Fig. 4, illustrates the manner of tying the sheared bar to the bar proper.

30 Referring by numerals to the drawings, 1 represents a bar having a web 2, and an integral bar 3, connected by a web 4, the bar 3, being substantially at right angles to the web 2. By shearing the web 4 from the respective ends of the bars towards the center, the ends of the bar 3, may be bent up at an angle from the bar 2, and parallel thereto as shown in Fig. 2, so as to obtain the effect of a continuous beam. The web 2, is sheared in sections 5, and said sections are bent up at right angles to the bar 2, as clearly shown. Any desired number of these sheared sections may be employed the number varying according to the strength it is desired to obtain. It is also to be understood that I may use two of these bars and tie the same together. The bar

3, is tied to the bar 1, by means of a strip 6, which is bent around the respective bars and provided upon its 45 respective ends with a clamp 7, such strips may be employed when two of the bars are used in place of one.

It will be seen that a beam or girder, armored in accordance with the construction above described, is rigid and will efficiently perform its intended function. 50 However, if additional strength is required a bar 8 may be placed parallel to the bar 1, and connected therewith by the strips above described.

In some cases it may not be necessary to employ the tie strips 6, and in the absence thereof the free ends of 55 the sections 5, may be bent over the bar 3, as shown at 9.

Having thus described the various features of my invention, what I claim as new and desire to secure by Letters Patent, is:

1. In an armored beam or girder, two parallel bars connected tangentially by a web, one of the bars being larger than the other, a second web upon the larger bar projecting tangentially therefrom and arranged at right angles to the first mentioned web, substantially as specified. 65

2. In an armored beam or girder, two parallel bars connected by a web, the web being cut so as to form bifurcated ends, the respective ends of one bar being bent at an angle from the other bar, a web upon the straight bar, said web being sheared in sections, the said sheared sections being 70 bent at right angles to the bar, substantially as specified.

3. In an armored beam or girder, two parallel bars connected by a web, one of the bars being larger than the other, a web upon the larger bar at right angles to the web connecting the bars, the web connecting the bars being sheared so as to form bifurcated ends, the respective ends of the smaller bars being bent at an angle from the larger bar, the web upon the larger bar being sheared in sections, said sections being bent at right angles to the bar, and the strap for tying the upper bar and the lower 75 bar together, substantially as specified.

4. In an armored beam or girder, two parallel bars connected by a web being cut so as to form bifurcated ends, the respective ends of one of the bars being bent up to obtain the effect of a continuous beam, a web upon the 85 other bar, said web being sheared in sections, said sheared sections being bent at right angles to the bar and clamped over the bent bar, substantially as specified.

PIERRE ZUCCO.
